(57) CLAIM

What is claimed is the ornamental design for a writing instrument, as shown and described.

DESCRIPTIONFIG. 1 is a perspective view of a writing instrument;
FIG. 2 is a front elevational view of the writing instrument of FIG. 1;

FIG. 3 is an enlarged top plan view of the writing instrument of FIG. 1; and,

FIG. 4 is an enlarged bottom plan view of the writing instrument of FIG. 1.

The broken lines are included for the purpose of illustrating environment and form no part of the claimed design.
